HAIR CURLER

Alice Phyllis Cunningham, New York, N. Y., assignor to Hair Net Packers, Inc., New York, N. Y., a corporation of New York

Application November 6, 1935, Serial No. 48,491

15 Claims. (Cl. 132—44)

This invention relates to improvements in hair curlers and more particularly to hair curlers that are not only effective to form attractive curls but are adapted to yield so as to avoid discomfort to the user, particularly at night while sleeping, and also to avoid injury to the hair.

An important object of the invention is to provide a novel and advantageous hair curler having the general characteristics above-mentioned. 10 Each curler may comprise two members or legs of yieldable material, rubber for example, adapted to be brought together to grip hair therebetween and then to be used to wind or roll the hair thereon, and an elastic member or strap extending over the roll of hair and embracing said legs at opposite ends of the roll. Preferably the legs are so shaped that the assemblage formed by bringing them together is tapered from one end to the other to facilitate withdrawal of the curler from the curls formed thereon. Ease of withdrawal may also be facilitated by making the surfaces of said legs very smooth. Such smoothness may result in insecure gripping of the hair between said legs but this trouble may be avoided by 15 suitable provisions at the engaging sides of said legs. The legs are preferably connected or hinged together at their large ends by a flexible connection integral with said legs. As to certain features of the invention, this application is a continuation of my copending application Ser. 30 No. 23,812, filed May 28, 1935.

According to a preferred embodiment of the invention, each curler is made of rubber in any suitable manner, as by molding, in a single straight piece with the large ends of the legs connected by means of a relatively thin part or strap, constituting a hinge. Each of the legs is preferably formed with a generally half-round section and with a taper extending substantially 40 to its outer end which is rounded so that, when the legs are brought together in folded relation on use, their outer ends will provide a rounded end for the curls as a whole. At their inner sides, close to the rubber hinge strap, the legs may be 45 formed with spacing projections. To improve the gripping action of the legs the hair-engaging portions of the legs may be provided with grooves extending longitudinally of the legs. The curler is normally kept in folded condition with the 50 spacing projections in engagement, the outer portions of the legs being bent away from each other in inserting the hair and the engaging spacing projections acting to hold the hair away from the strap hinge. Said legs may be held in folded 55 position in any suitable manner but preferably

by an elastic device surrounding the large ends of the legs and seated in corresponding semi-circular grooves in the outer surfaces of the legs. This elastic device may be a perforated end of an elastic member or strap having one or more other perforations at another part so that the strap may be carried over a roll of hair on the curler and secured in position by insertion of the rounded ends of the legs in one of said other perforations in accordance with a desired adjustment. Due to the tapered shape of the legs, the farther the perforated portion of the strap is pulled over the free ends of the legs the greater the pressure urging the two legs toward each other. The legs of the curler while adapted to hold their shape sufficiently to meet all requirements are sufficiently soft and flexible to conform sufficiently to the portion of the head, which may be engaged thereby, to avoid discomfort.

Other objects, features and advantages will appear upon consideration of the following description and of the drawing in which

Fig. 1 is a view illustrating a preferred embodiment of the hair curler of the present invention with hair rolled thereon and secured in position;

Fig. 2 is a top plan view of the body of the curler in extended position as molded;

Fig. 3 is an edge view of the member shown in Fig. 2;

Fig. 4 is a view of the complete curler with the legs folded together and held together at their large ends by the corresponding perforated end of the hair-holding elastic member or strap;

Fig. 5 is a plan view of the elastic strap;

Fig. 6 is a cross section of the arms of the curler when in the closed position of Fig. 4; and

Fig. 7 is a view similar to Fig. 6 but illustrating a modification.

Referring to the drawing, there is illustrated a hair curler comprising an elongated body 10 having a short central portion or hinge 11 and end portions or legs 12 and 13 which may be substantially identical, and means, in the form of an elastic strap 14 having at one end a perforation 45 or opening 15 to receive the hinge ends of the legs and at the other end one or more openings 16 to receive the outer or disconnected ends of the legs, for holding the legs together to grasp therebetween hair that is to be wound or rolled 50 thereon and for engaging hair 17 on the curler legs and holding it in position as well as subjecting it to some pressure.

The curler may be of any suitable material but preferably is made of rubber having suitable 55

characteristics and the body portion in the form shown in Figs. 2 and 3 is formed as by molding. The body portion, in its original and open position, may be and preferably is of substantially 5 semicircular cross section throughout, and the legs are tapered so as to decrease in cross section from their inner ends to their outer ends, especially to facilitate removal of the curler from a roll of hair thereon. The outer ends of the legs 10 are preferably shaped so as to avoid corners or any formation which would tend to catch the hair, and this result may be obtained by rounding the ends of the legs so that when they are brought together as shown in Fig. 4 they present substantially the surface of a hemisphere. Preferably the surface is made as smooth as possible and particularly good results have been obtained by applying a coat of suitable lacquer, as by dipping. When, however, the surface is 15 very smooth, it is more difficult to hold the hair firmly between the legs 12 and 13. This difficulty may be overcome by suitable provisions at the inner sides of the legs. As illustrated in Figs. 2 and 6 this result may be obtained by providing the inner side of the leg 12 with three longitudinal grooves or valleys 18 separated by ridges 19, and the inner side of leg 13 with two longitudinal grooves or valleys 18, opposite the ridges 19 of leg 12, and a separating ridge 19 20 opposite the middle depression of leg 12.

The hinge portion 11 of the body 10 may be formed at the base of a deep notch 20 at the rounded side of the central portion of the body 12 and this central portion is preferably formed at 25 its inner side with flat projections or spacing devices 21 at the inner side of the body, whereby if the legs 12 and 13 are folded together, as in Fig. 4, the legs are spaced apart adjacent to these spacing devices or projections to provide for more 30 even spacing of the hair and prevent it from being moved in too close to the hinge.

The legs 12 and 13 may also be provided with 35 grooves 22 in their outer sides opposite the outer ends of the spacing projections 21. When each leg is half-round as illustrated, each groove is substantially a half circle and the two grooves form substantially a complete circle around the inner ends of the folded arms. While the same 40 general result may be obtained in various other ways, these grooves determine the position where pressure, to hold the legs together, is provided by suitable means such as the strap 14 whose end may, by virtue of the opening or perforation 45 15, be stretched over the hinged ends of the legs 50 and be seated in said groove.

With the parts positioned as in Fig. 4, the legs 55 12 and 13 may be separated, as by bending, sufficiently to insert therebetween hair to be curled. The hair is then wound or rolled about said legs 60 and forces them together to maintain a firm grip or grasp on the hair positioned between said legs 12 and 13. When the winding or rolling is completed, the elastic strap 14, or other suitable extensible resilient device, is stretched across the 65 wound hair 17 and secured in position by placing one of said perforations or openings 16 over the outer ends of said legs 12 and 13 thereby urging them toward each other. The plurality of the openings 16 enables adjustment of the tension of 70 the strap 14.

In Fig. 7, there is illustrated a modified form 75 of gripping or grasping means at the inner sides of legs 12a and 13a—leg 12a being provided at its inner side with a projecting longitudinal rib 23 of wedge-shape in cross section, leg 13a being

provided with a corresponding longitudinal recess or valley 24 to receive said rib, and said rib and said recess being provided with grooves 18 and ridges 19 arranged in the same general manner as grooves 18 and ridges 19 in Fig. 6.

It should be understood that various changes may be made in construction and arrangement and that various features may be used without others without departing from the true spirit and scope of the invention.

Having thus described my invention, I claim:

1. A hair curler comprising two yieldable legs between which hair can be grasped and around both of which hair thus grasped may be wound, spacing means between the legs at one end of the 15 curler acting to hold the legs separated at such end of the curler, means yieldably pressing said legs toward each other over said spacing means, and an extensible member extending from said end of the curler, and having a part to hold the 20 legs together at the other end of the curler.

2. A hair curler comprising an elongated member of resilient rubber having a central flat hinge portion about which the member is folded to provide legs between which may be grasped hair 25 which is then wound therearound, said legs having spacing projections at their inner sides adjacent to the hinge portions to leave a space for the hair between the legs adjacent the spacing projections, and an elastic strap having a perforated end embracing the legs at their hinge ends to press said spacing projections against each other and another perforated portion to embrace the other ends of the legs and hold them together as well as hold the elastic strap under tension 30 35 against hair wound around said legs.

3. A hair curler comprising two yieldable legs between which hair can be gripped and around both of which hair thus gripped may be wound, said legs in gripping position providing a core 40 of substantially circular cross section and tapered from a larger end provided by larger ends of said legs down to a smaller end formed by smaller ends of said legs, spacing means between the larger ends of said legs acting to hold the 45 legs separated at such ends, means for holding said legs together at their large ends as determined by said spacing means, and said holding means comprising an elastic strap embracing the large ends of said legs and having a perforated 50 portion to go over the smaller ends of said legs to urge the same together and also to hold the elastic strap against hair wound on said legs.

4. A hair curler comprising a single piece member of rubber having a central flat portion 55 constituting a hinge and at opposite ends thereof leg members adapted to be brought together to grip hair therebetween and serve as a core on which hair so gripped is wound, said legs being of generally half-round cross section and tapering from their hinged ends down to their free ends, said legs having spacing projections at the inner sides of said legs adjacent to said hinge tending to space the inner surfaces of said legs away from each other adjacent to said projections, and at their large ends substantially semicircular grooves arranged to form a circular groove when the legs are folded together, and an elastic strap having a perforated end embracing said legs and seated in said semicircular grooves and another perforated portion adapted to receive the smaller ends of the legs and hold them together and hold the strap against a roll of hair on said legs.

5. A hair curler comprising two legs adapted 75

5 to grip hair therebetween and then serve as a core on which hair may be wound, one of said legs having a V-shaped longitudinal groove at its inner side and the other having at its inner face a corresponding rib to enter said groove, the sides of said groove and said rib being provided with alternate ridges and valleys.

10 6. A hair curler consisting of a strip of resilient rubber folded upon itself to provide contacting legs, each of the legs being formed with an external groove and the grooves of the legs registering with each other, and an elastic strap having a loop stretched over the connecting portions of the legs and fitted edgewise in said grooves 15 and having another loop in the opposite end thereof adapted to be stretched over the ends of the legs, whereby the hair may be first inserted between the legs and then wound over both legs and then placed under compression by connecting the second loop of the strap with the ends of the legs; said first loop forming an elastic connector for both legs adapted to permit the same to separate when hair is placed between the legs.

20 7. A resilient hair curler comprising a one piece member having integrally associated and complementary hair gripping means including a hinge connection, and an elastic element having one end mounted on said member to hold said 25 complementary means closed adjacent said connection and including another end disconnectably associated with a remote end of said member to hold said remote end closed.

8. A resilient hair curler comprising a foldable one piece member having hingedly connected portions, and an elastic element mounted on said member to hold corresponding end portions thereof closed.

30 9. A resilient elongated foldable member comprising hinged legs having rectilinear surfaces adapted to grip hair interposed therebetween, and means to hold said surfaces in close proximity and corresponding end portions of said legs closed.

10 10. A foldable curler comprising an elongated member defining spaced legs and attenuated means integrally interconnecting said legs to characterize a hinged connection to permit said legs to separate or be brought towards one another to grip hair interposed therebetween, and an elastic member comprising a loop for holding said legs adjacent said connection closed and means for closing said legs remote from said connection.

15 11. A foldable curler comprising an elongated member defining interconnected swingable legs adapted to be brought towards each other to grip hair interposed therebetween, and an elastic stay having means for holding corresponding portions 15 of said legs substantially at the ends thereof closed.

12. A resilient hair curler wherein an elastic curler comprises foldable means to grip the hair characterized further in that an elastic element 20 having spaced loop means is disconnectably mounted at the ends thereof.

13. A foldable member for gripping hair and an elastic stay carried thereby and comprising means for holding remote ends thereof substantially closed.

14. A foldable resilient member for gripping hair, and an elastic member mounted thereon and adapted to hold complementary portions of said member in close proximity to sustain the 30 hair wound about said member under pressure.

15. A hair curler comprising an elongated member of sensibly resilient rubber having a substantially centrally disposed attenuated portion and including laterally extending hair clamping 35 legs having inner ends integrally merged with said attenuated portion, said attenuated portion constituting a hinge interconnecting said inner ends, means for yieldingly urging said ends together, said legs having outer ends, and urging 40 means comprising a sensibly elastic member having a portion for receiving said outer ends to prevent separation of the latter.

ALICE PHYLLIS CUNNYNGHAM.
